WASHBOARD

Charles T. Gilbert, Saginaw, Mich., assignor to
 National Washboard Company, Chicago, Ill., a
 corporation of West Virginia

Application June 18, 1934, Serial No. 731,096

3 Claims. (Cl. 68—29)

This invention relates to wash-boards and pertains more particularly to improvements in a wash-board rubbing face structure of the kind having ribs and grooves or valleys of approximately equal width that extend in the direction of rubbing, lengthwise of the wash-board. Such arrangement of the corrugations is shown and described in a copending application, Serial No. 724,314, filed May 7, 1934, and in another copending application, Serial No. 724,700, filed May 9, 1934. I have shown a double-faced board wherein the corrugations of one of the two faces extend up and down, that is, lengthwise of the wash-board. Both of said applications and my present invention are owned by a common assignee of record. In those applications it is set forth that a rubbing surface having ribs and valleys extending in the direction of rubbing is advantageous because the area of working contact between a handful of goods and the rubbing surface is much greater than with a surface having horizontally extending ribs, the speed of washing is increased, the amount of pressure required to be exerted against the board is reduced, and stretching and other harmful effects on delicate fabrics are minimized. Also, there is better drainage from the clothes while they are being rubbed.

The improved rubbing face structure herein described differs from the structures shown in both of the above-mentioned copending applications in respect to the crests of the up-and-down ribs and the bottom and side walls of the intervening grooves, whereby the objects are attained.

The objects of my present improvement are, to produce as an article of manufacture a rubbing surface capable of washing without straining, tearing or stretching, such delicate fabrics as laces, articles made of artificial silk, sleazy fabrics, lingerie and the like; to minimize the cost of manufacture of rubbing elements of that character by providing a rib-and-valley structure having maximum resistance to springing or bending with minimum weight and thickness of material; and to improve the appearance of the wash-board.

With the foregoing and certain other objects in view, which will appear later in the specifications, my invention comprises the devices described and claimed and the equivalents thereof. It is to be understood that specific embodiments herein illustrated and described are chosen as preferred structures typical of others that may be constructed by those skilled in the art, and that the invention set forth in the appended claims is not intended to be limited further than is required

to distinguish from wash-board rubbing elements known before.

Fig. 1 is a front view of a wash-board showing a fragmentary rubbing surface made according to my invention.

Fig. 2 is a horizontal sectional view on line 2—2 of Fig. 1.

Figs. 3, 4 and 5 are detail views, showing various preferred novel forms of ribs and valleys for the sheet metal rubbing element.

As is clearly shown in the drawing, the rubbing element to which my present improvement is applicable comprises a sheet formed with parallel corrugations that extend up-and-down lengthwise of the board. These corrugations present laterally alternating ribs 1 and grooves 2, their general shape in cross section may be ogee curves that define a series of crests and valleys extending from the top 3 of the rubbing surface of the wash-board to its bottom 4. Any other than ogee shaped corrugations may be employed if desired.

In the form shown in Figs. 3 and 5 the valleys 2 between the ribs 1, and preferably also the side walls 5 of the ribs, are embossed so as to present a great number of humps, bulges or raised portions 7 which are separated from each other by depressions 8.

The bulges 7 may be formed by first embossing a flat sheet of thin metal according to an appropriate pattern, such as a multitude of conventional diamond shapes, or any other fine design, and then passing the embossed sheet through corrugating rollers to form the ribs 1 and valleys 2, the height of the embossments in the valleys 2 being practically the same as in the original embossed sheet, while the embossments up the sides 5 of the ribs are somewhat flattened, and on the crest 6 of each rib the surface 6a is nearly smooth, the embossments showing slightly as in Fig. 3, or scarcely at all.

Another satisfactory arrangement of the rubbing surface is obtained by forming in a flat sheet embossments of the pattern desired for the valleys and side walls, the embossed areas being in the form of parallel bands spaced apart, the intermediate parts of the sheet being left smooth, then passing the sheet through corrugating rolls so that the smooth portions of the sheet will become the crests 6 of the ribs 1, as shown in Fig. 5, and the embossed parts will become the valley bottoms 2 and the side walls 5.

The rubbing surface herein described possesses characteristics that make it greatly superior to surfaces heretofore used. The rubbing is done

up and down lengthwise of the ribs, and a handful of delicate fabrics being rubbed rides principally on the rib crests but fills the grooves 2 and in them is subjected to the rubbing action of the 5 embossments 7 on the bottom and side walls 2, 5. The goods are not subject to any appreciable rubbing strains at the smooth, or approximately smooth crests 6 of the ribs 1. Since the face of the mass of wet goods squeezes into and fills the 10 grooves, it will have a very much larger total area exposed to the rubbing action of the embossments at 7 and 5 than the same handful would have if it were rubber crosswise of the corrugations. This will be apparent when it is remembered that the face of the mass of goods fits itself lengthwise to the contour of the grooves 2 and consequently the total width of the area being worked is the developed instead of the projected area of the corrugated sheet.

20 According to this invention, the crests 6 of the ribs produce a relatively small amount of interference to rubbing. They may be perfectly smooth, as shown in Fig. 4, or as previously described; they may have only slight bulges and 25 depressions, Fig. 3. The crests 6, therefore, form a series of supporting surfaces to take most of the rubbing pressure load, somewhat like a series of parallel tracks, up and down which the mass of goods is rubber, while in between the tracks 30 the material is squeezed into the grooves or valleys 2, and is there acted upon by the bulges or embossments 7 on the bottoms 4 or sides 5

of the grooves, or both. Excessive rubbing pressure on the goods is avoided, because the smooth crests 6 take most of the load and only slight pressure can be exerted on the embossments at the bottoms of valleys 2. The vertical disposition of the grooves 2 affords perfect drainage.

Having thus described my invention, what I claim and desire to secure by Letters Patent is:

1. A rubbing element for wash-boards comprising a sheet metal structure presenting alternating parallel ribs and grooves or valleys disposed lengthwise of the direction of rubbing, the bottoms of said valleys being formed with a plurality of embossments spaced apart, the crests of the ribs being substantially smooth.

2. A structure as set forth in claim 1 wherein the side walls of the ribs below the crests are formed with alternating raised portions and depressions.

3. A rubbing element for wash-boards comprising a plate-like member having a surface thereof formed to present alternating parallel ribs and valleys of substantially equal width disposed lengthwise of the direction of rubbing, the crests of said ribs being substantially smooth, the work-engaging faces of the valleys being formed with raised portions alternating with depressions, the raised portions in the bottoms of the valleys being more pronounced than those on the side walls thereof.

CHARLES T. GILBERT.
